RAZOR BLADE KNIFE

Martin Glaberson, Ardsley, N. Y., assignor to Eversharp,
Inc., New York, N. Y., a corporation of Delaware

Application September 10, 1957, Serial No. 47,690

Term of patent 14 years

(Cl. D22—3)

Fig. 1 is a side elevational view of a razor blade knife, showing my new design;

Fig. 2 is a top plan view thereof;

Fig. 3 is a bottom plan view;

Fig. 4 is an enlarged left end elevational view of the razor blade knife shown in Fig. 1;

Fig. 5 is an enlarged right end elevational view thereof;

Fig. 6 is a side elevational view as it appears with the blade in open position; and

Fig. 7 is a top plan view thereof.

I claim:

The ornamental design for a razor blade knife, substantially as shown.
